COMBINED CIGARETTE HOLDER, SMOKER,
AND ASH-RETAINER

Norman Coffelt, Glen Burnie, and Sterling P. Buck, Baltimore, Md., assignors of two-thirds to said Coffelt and one-third to said Buck

Application December 17, 1936, Serial No. 116,342

9 Claims. (Cl. 131—175)

This invention relates to ash-retaining cigarette-pipes, or combined cigarette holder, smoker and ash-retainer.

In brief, concise and broad terms, the invention consists of a tube having one end permanently closed and its other end open when inserting a cigarette, but closed when the cigarette is being smoked, except for a draught-duct in the mouth-piece which is hinged to the originally open end and constitutes the closure therefor while also combining therewith to form a clamp that secures the cigarette in smoking position and relation, securing or latching means being provided to move or be moved into and out of position for keeping the closure in the closing and clamping position; means also being provided to close and open air-inlets in the upper side of the tube, so as to prevent spilling of ashes when closed; all as shown in the seven figures of drawing that are signed and dated on this 4th day of December, 1936.

It is well known that many destructive and costly conflagrations have been started by lighted cigars and cigarettes, and by incandescent ashes falling therefrom into or onto papers, leaves, dry grass, lint in factories, bed-clothes etc.; that costly articles of clothing, carpets, rugs, table covers and furniture have been spoiled or disfigured by smokers thoughtlessly laying or inadvertently dropping lighted stumps of cigars and cigarettes on such articles; and that, regardless of these dangers and annoyances, there is that unsightly aspect of ashes dropped on floors, carpets, rugs and tables; all these dangers and annoyances being avoidable; and one object of this present invention is to avoid, obviate or preclude them.

Another object of the invention, therefore, is to meet the great and growing need of the present generation of smokers, especially those who smoke while motoring, to avoid accidents such as often occur by the driver's attention being diverted by ashes falling on his clothes or blowing into his eyes; to avoid forest fires by hunters or campers whose ashes or lighted stumps so often fall into dry leaves or grass and cause fires that destroy forests, field crops, houses, villages and lives; and to avoid loss of property and lives sometimes caused by persons smoking in bed or in upholstered chairs where they fall asleep and let the lighted cigar or cigarette fall and start the fire.

A further object is to provide a safe and satisfactory tube, pipe or housing in which a cigarette or cigar can be smoked, laid on papers, table covers, varnished surfaces, marble etc., or put into pockets, hand-bags and other receivers, without

danger or detriment to anything or any person; thus meeting the needs of the great majority of smokers of both sexes.

Another object of this invention is to improve upon inventions of a similar character but which have inconvenient and otherwise objectionable features and which lack some of the important features which are shown in the accompanying drawing and specifically described hereinafter.

Other objects and important features are pointed out or implied in the drawing in connection with the following details of description, wherein, similar reference numerals refer to similar parts in the several views of the invention.

Fig. 1 is a side elevation of one form of the invention, showing the approximate size used in connection with standard-size cigarettes; but it is understood that this size and shape can be changed to suit different sizes of cigarettes and cigars, as circumstances may dictate.

Fig. 2 is an enlarged view in longitudinal section, showing a part of a cigarette in dot-dash lines within the housing, and the combined mouth-piece, closure, and lower clamp-jaw in its normal clamping and smoking position in full lines, and turned up and over in dot-dash lines.

Fig. 3 is a view similar to Fig. 2, but showing certain modifications of several features, the combined mouth-piece, closure and lower clamp-jaw being in the wide-open position, the curved lines showing the relation of elements of the closure to the main tubular part of the housing when in the normal position.

Fig. 4 is a sectional view at the line 4—4 of Fig. 2.

Fig. 5 is a sectional view at the line 5—5 of Fig. 3.

Fig. 6 is a sectional view at the line 6—6 of Fig. 2.

Fig. 7 is a detail view of an annular closure fastener such as shown in Figs. 1, 2 and 3, either having a point secured to the tubular main member, or free to be slid along the latter against frictional resistance.

Referring to Figs. 1 and 2 of the drawing, it is seen that the tubular member 10 has an initially or primarily closed outer end 11, an annular boss or ridge 12, a corresponding annular inner groove 13, an opening or slot 14 which constitutes an air-inlet, and an acute-angled inner end 15 which may also be described as diagonal, longitudinally projecting or over-hung. A hinge 16 is secured to the acute end or over-hung part, and one wing of this hinge may be formed integrally with an upper lip or clamp-element 17 that is secured or

united with the member 10 by any appropriate means. The other wing of the hinge 17 may be an integral part of the combined mouth-piece, closure and clamp-jaw which is generally indicated at 18, has a diagonal end 19 normally close-fitted against the end 15, has a draught-duct 20 through the mouth-piece 21, and has a lower jaw or lip 22 that is preferably provided with short and sharp teeth 23; so, when the parts are in normal position, as shown in Figs. 1, 2 and 6, the overlapping or interlapping ends of the members 10 and 18, with their jaw-elements 17 and 22, form a restricted mouth or clamp that but slightly compresses the end of the cigarette or cigar held thereby in the position for being smoked through the mouth-piece 21. The lateral edges of the lips 17 and 22 are preferably chamfered or thinned so as to slightly widen the mouth and prevent pinching and tearing the wrapper of the cigar or cigarette being clamped therein; and this also permits the clamped end of the cigar or cigarette to spread laterally, so the draught therethrough is not hindered by the end of the cigar or cigarette being clamped. Moreover, to minimize the necessary clamping and depressing of the end, one or more of the teeth entering the clamped end, will prevent the end from slipping out of the clamp in the event the device falls or otherwise receives a jar or impulse that would tend to displace the cigar or cigarette from its clamped smoking position. In Fig. 2, a partly consumed cigarette is indicated at C in dot-dash lines.

To secure the member 18 in its closed or closing position, and permit it to be opened and closed at will, any appropriate catch or keeper or locking means may be employed; and a very simple and effective means is shown at 24 (Figs. 2, 3 and 7) in the form of a ring which is preferably split or open at 25 and may be secured at 26 to the member 10 so it is not movable bodily, but can be sprung at the opening 25 by pressure of the angular end of the member 18 when moving to the closing position, then springs back by its own inherent elasticity so as to engage with the member 18 for holding it in the closing position. When desired to open the member 10 so as to insert a lighted cigarette, the free ends of the ring or keeper 24, at the opening 25, may be pushed by means of a finger or thumb out of engagement with the member 18 while the latter is turned on its hinge 16.

In Figs. 2 and 4, the air-inlet 14 is shown closed by a combined heat insulating tube, handle and air-inlet closure 27 which is longitudinally slotted or split at 28 and is slidable on the member 10 against a slight resistance in consequence of its springy clamping action on the member 10; so it can be turned from the position shown, to such position that the openings 14 and 28 are in registration with one another, and so the air can then be sucked therethrough and through the cigar or cigarette by the smoker, and so the air-inlet can be closed by the member 27 when the user wishes to prevent ashes from spilling into a pocket or hand-bag into which the device is placed for carrying it. The lower side of the member 27 may be formed with a foot 29 having a flat or plane under side to prevent the device from rolling or turning over and spilling ashes when laid on a table, desk or other surface, and the vertical surfaces or lateral sides of the portion or foot 29 serve as manipulative means for easily turning the member 27 to and from the closing position without increasing the friction between the members 27 and 10.

At 30, a length of wire is secured with its ends in the groove 13 and serves as means to hold the cigarette away from the end of the housing so as not to interfere with the free passing of air into the lighted end of the cigarette. 5

In the modifications shown in Figs. 3 and 5, the main tubular part 10a has its initially open outer end closed by an imperforate cap or cup 11a fitted thereover and secured by any appropriate means, as by a slender rivet 30a which also serves as a stop or rest for the lighted end of a cigar or cigarette; while the rim of the member 11a serves the same purpose as the ridge 12 (Figs. 1 and 2), to prevent the member 27 or 27a from being pushed too far forward on the member 10 15 or 10a. In the foregoing, the words "has its initially open outer end", are intended to mean that the outer end was open before the cap or cup was placed thereon for closing it. The dual rectangular construction shown at 15a is deemed 20 less practical than the diagonal or oblique construction at 15 (Figs. 1 and 2); but it here illustrates, in connection with the complementary construction of the member 18a, that the invention is not limited to the overhung and interlapped 25 construction previously explained. The longitudinally extending upper lip 17a is only slightly different from the part 17 and serves the same purpose in combination with the parts 22 and 23. In this modified form, the springy open ring 24 30 is bodily movable from its full-line position to its dot-dash line position and to other positions against a slight frictional resistance which normally holds it wherever placed by the user; and it is seen that when the parts 10a and 18a are in 35 their normal aligned position while the keeper 24 is in its dot-dash position, the parts are secured thereby in their clamping relation with respect to a cigar or cigarette within the device. In lieu of the slots 14 and 28 shown in Figs. 2 and 4, 40 two or more openings, or even a single opening in each of the elements 10a and 27a may be provided of any desired size and shape, as indicated at 14a and 28a (Figs. 3 and 5).

While the invention is not limited to these details as shown and described, and not to any specific material or materials, it is contemplated that they are essentially non-combustible, and that the parts 18, 18a, 27, 27a and 24 should be heat-insulating material such as Bakelite or the like, so the heat from the lighted cigar or cigarette will not burn the hands or mar any piece of furniture on which the device may be laid; but it may be preferable to make the parts 10, 10a, 11 and 11a of silver, aluminum or an alloy, so 55 the user can ascertain, by locating the hottest part, to what extent the cigarette has been consumed.

In using the device, the cigar or cigarette is lighted and dropped into the open end of the member 10 or 10a, the member 18 or 18a is then moved to its normal position, thereby clamping the cigarette or cigar as indicated at the right end portion of Fig. 2; then if the member 27 or 27a is at the air-admitting position, the device 65 is ready for smoking, and it is obvious that the fire and ashes cannot escape; but when the device is opened, the ashes may be emptied through the open end of the tubular member 10 or 10a.

What we claim as our invention is:

1. In a device for the purposes specified, the combination of a tubular element having a closed end and an initially open end and having an air-inlet at its upper side, means to close and open said air-inlet, and a combined tubular 75

5 mouth-piece and closure permanently and movably secured on said initially open end and comprising means for cooperating with said initially open end in proper relation for clamping a lighted cigar or cigarette in smoking relation with said mouthpiece and air-inlet.

10 2. The structure defined by claim 1, the last said means including a hinge which is engaged with said tubular element and combined tubular mouthpiece and closure so as to connect these elements together and in pivotal relation to one another.

15 3. The combination defined by claim 1, the air-inlet closing means being a tubular element on and frictionally embracing the first said tubular element and slidably thereon by manipulation of the user to and from positions for closing and opening the air-inlet.

20 4. The combination defined by claim 1, the said tubular element having one side of its initially open end projecting longitudinally as specified, said combined tubular mouth-piece and closure being hinged to said initially open end and having an end complementary with and normally interlapping with said initially open end so as to co-act therewith and with the hinge for clamping an end of a cigar or cigarette which is mainly within said tubular element, and releasable means to secure said tubular element and combined 25 mouth-piece and closure normally in their operative clamping relation.

25 5. In a device for the purposes specified, the combination of a tubular element adapted to receive a cigar or cigarette and having an air inlet therein and having an initially open end, a combined mouth-piece and closure in interlapped engagement with said initially open end in cooperative relation with the latter to form a clamp for engagement with said cigar or cigarette so as 30 to hold the latter against movement relative to the tubular element, said clamp having lips in the proper relation to hold the cigar or cigarette in spaced relation to the inner surface of the tubular element so as to obviate excessive heating of the latter by the cigarette or cigar when lighted, 35 the other end of said tubular element being closed and imperforate and provided with means to keep the cigar or cigarette spaced therefrom.

6. In a device for the purposes specified, the combination of a tubular receptacle and a tubular mouth-piece element hinged to one another and having substantially diagonal ends normally fitted together in interlapped relation and being 5 cooperative for engaging and holding a cigar or cigarette which may be placed therein, and means secured thereon and movable to and from a position for securing the diagonal ends in their cooperative relation to one another. 10

7. In a device for the purpose specified, the combination of a tubular element having initially open ends and having an air-inlet at its upper side, means to close and open said air-inlet, imperforate means normally closing one of said initially open ends of said tubular element, and a combined tubular mouth-piece and closure permanently and movably secured on the other one of said initially open ends and comprising means for cooperating with said other one of the initially 20 open ends in proper relation for clamping a lighted cigar or cigarette in smoking relation with said mouthpiece and air-inlet substantially as described. 15

8. The combination defined by claim 7, the last 25 said means being inclusive of a hinge which is engaged with said tubular element and combined tubular mouthpiece and closure so as to connect these elements together in movable and cooperative clamping relation to one another. 30

9. In a device for the purpose specified, the combination of a tubular element having initially open ends and having an air-inlet at its upper side, means to close and open said air-inlet, means normally closing one of said initially open 35 ends of said tubular element, the other one of said open ends being substantially diagonal, and a tubular mouthpiece having a substantially diagonal end hinged to the diagonal end of said tubular element so as to be permanently secured there- 40 to while being movable from a normally interlapped relation for clamping a cigar or cigarette and movable to an open position for permitting the cigar or cigarette to be inserted in and removed from said tubular element substantially 45 as described.
